UNITED STATES PATENT OFFICE.

JAY M. JOHNSON, OF CHICAGO, ILLINOIS, ASSIGNOR TO JOHNSON COIN COUNTING MACHINE COMPANY, A CORPORATION OF NEW YORK.

COIN INSPECTION AND COUNTING MACHINE.

1,251,534.

Specification of Letters Patent.

Patented Jan. 1, 1918.

Application filed February 20, 1917. Serial No. 149,926.

To all whom it may concern:

Be it known that I, JAY M. JOHNSON, a citizen of the United States, and a resident of the city of Chicago, in the county of Cook and State of Illinois, have invented certain new and useful Improvements in Coin Inspection and Counting Machines; and I do hereby declare that the following is a full, clear, and exact description of the same, reference being had to the accompanying drawings, and to the numerals of reference marked thereon, which form a part of this specification.

This invention relates to an improved form of coin counting machine wherein the coins to be counted are carried upon a conveyer into the field of observation of an inspector, so that defective or counterfeit coins may be removed before passage to the counting mechanism. The invention embraces a traveling conveyer adapted to carry coins thereon from a hopper into which the coins are dumped, to a counting mechanism, said conveyer comprising a plurality of pans or trays mounted upon the links of traveling chains and moving at a relatively slow speed in position for inspection of the coins carried thereon before discharge of the coins to the coin counting mechanism.

It is an object therefore of this invention to construct a coin inspection and counting machine wherein a conveyer comprising a plurality of overlapping trays is provided to convey coins thereon from a receiving hopper toward a counting mechanism so that the coins may be inspected prior to their introduction into the counting mechanism and undesirable coins removed to table extensions formed on each side of the machine by sliding the coins from the tray elements at the open ends thereof.

It is also an object of this invention to construct a high speed coin handling machine embracing a tray conveyer for conveying coins from a hopper to a counting mechanism in a manner permitting inspection of the coins and discharging the coins into the counting mechanism which serves to operate the coins centrifugally and feed the same singly to counting mechanisms where-

in the coin itself acts as a mechanical element to actuate the mechanisms assisted by an auxiliary driven friction wheel so that a large number of coins may be counted in a short space of time.

It is also an object of this invention to construct a high speed coin counting machine wherein the coins are conveyed by a tray conveyer permitting inspection thereof to a counting mechanism embracing a rapidly rotating disk which discharges the coins centrifugally to its outer periphery and serves to feed the same singly to a counting mechanism wherein the coins each act as a mechanical element assisted by power driven means to actuate the counting mechanism and with mechanism adjustable for co-action with said coin carrying disk to limit the machine to operation upon coins of a predetermined denomination.

It is furthermore an important object of this invention to construct a coin handling machine wherein the coins are displayed for inspection and then discharged to a counting device which operates upon the coins separating the same centrifugally for admission singly to the register actuating means, and with automatic mechanisms associated with said register means to stop the operation of the machine after a predetermined number of coins have been counted.

It is finally an object of this invention to construct a coin inspection and counting machine which may be set to count a predetermined number of coins, and which is operable upon coins of different denominations by adjustment of certain means which limit the machine to operation upon coins of a certain denomination.

The invention (in a preferred form) is illustrated in the drawings and hereinafter more fully described.

On the drawings:

Figure 1 is a side elevation of a machine embodying the principles of my invention.

Fig. 2 is a top plan view thereof.

Fig. 3 is an enlarged top plan view of the counting mechanism of the machine detached from the supporting frame and conveying means.

Fig. 4 is a detail section taken on line 4—4 of Fig. 3, with parts shown in elevation.

Fig. 5 is a detail section taken on line 5 5—5 of Fig. 3.

Fig. 6 is a detail section taken on line 6—6 of Fig. 3, with parts omitted.

Fig. 7 is a transverse vertical section taken through the friction coin driving wheel shown 10 in Fig. 6.

Fig. 8 is a fragmentary detail plan of the centrifugal coin wheel with the mechanisms thereabove omitted.

Fig. 9 is a detail section taken on line 15 9—9 of Fig. 3.

Fig. 10 is a fragmentary sectional view on line 10—10 of Fig. 4, with parts omitted.

Fig. 11 is a sectional detail on line 11—11 20 of Fig. 2, with the conveyer element shown in elevation.

Fig. 12 is a fragmentary detail view illustrating a part of the gearing which operates the automatic shut-off for the drive of the machine.

25 Fig. 13 is a fragmentary side elevation of one of the sprocket wheels of Fig. 11, showing the adjustment of the conveyer trays as the chain travels around the wheel.

30 Fig. 14 is a sectional detail taken on line 14—14, of Fig. 1, with parts omitted and parts shown in elevation.

Fig. 15 is a fragmentary end view of a portion of a conveyer chain with the trays attached on the links thereof.

35 Fig. 16 is a fragmentary sectional view taken on line 16—16 of Fig. 2, with parts shown in elevation.

Fig. 17 is a sectional detail view taken on line 17—17 of Fig. 8.

40 Fig. 18 is a sectional detail view taken on line 18—18 of Fig. 17.

Fig. 19 is a fragmentary sectional view illustrating in plan view a portion of the release mechanism associated with the counting 45 devices taken on line 19—19 of Fig. 5.

As shown on the drawings:

The machine is mounted upon a frame structure comprising four legs 1, supporting 50 at their upper ends side wall members 2 and 3, respectively. As clearly shown in Figs.

2 and 11, an inclined plate 4, is mounted between the side walls 2 and 3, at one end thereof, affording a hopper or coin receiving member and disposed beneath the lower end 55 thereof is a roller 5, journaled in arms 6, pivoted on the interior surfaces of said side walls 2 and 3, against which the lower edge of said plate 4, bears. Extending horizontally between the respective side wall

60 members 2 and 3, are shafts 7 and 8, respectively, and mounted thereon for rotation are pairs of sprocket wheels 9 and 10, respectively. A pair of chains 11, are trained around the respective pairs of

65 sprocket wheels 9 and 10. Alternate links

of the respective chains 11, have attached thereon lug extensions 12, of trays or pans 13, which extend from one chain to the other, and, as clearly shown in Fig. 15, the forward margins of each of said trays or 70 pans 13, is struck upwardly to overlap the rearward upturned edge of the preceding tray or pan. Guide members 14, are secured upon the inner surfaces of the respective side wall members 2 and 3, as clearly shown 75 in Fig. 11, to afford a support for the upper rims of each of the conveyer chains 11.

A pair of brackets 15 and 16, respectively, are disposed beneath the respective side wall members 2 and 3, at the forward ends thereof, and journaled therebetween is a shaft 17. Journaled on one end of said shaft is a sprocket wheel 18, the hub of which affords one element of a jaw clutch, and the other element of which is denoted by the reference numeral 19, and is feathered upon said shaft 17, so as to be slidable out of engagement with the hub of said gear. A sprocket wheel 20, is secured upon the outer end of the said shaft 17, and trained thereabout is 90 a chain 21, which is also trained about a sprocket wheel 22, secured upon said shaft 8. Thus, the conveyer chains 11, are driven by the respective sprocket wheels 9 and 10, from the shaft 17, when the clutch element 95 19, is in its engaged position.

Mounted in a forward extension of the respective bracket members 15 and 16, is a shaft 23, and journaled on the outer end thereof is a pulley wheel 24, driven by a 100 belt 25, which is also trained around the driving pulley of an electric motor 26, which is mounted on a frame member 27, extending between the legs 1, of the frame, as clearly shown in Fig. 1. Keyed or otherwise secured rigidly upon said shaft 23, is a small wheel 28, the periphery of which fits within a circular flange extension of the pulley 24, as clearly shown in Figs. 17 and 18, and pivoted upon said wheel 28, is a 110 pawl 29, which has connected upon the tail extension thereof a spring 30, which normally causes said pawl 29, to be thrown outwardly to permit engagement thereof with a notch in a circular flange portion of the pulley wheel 24, whereby the wheel 28, 115 may be driven by the wheel 24. Slidably mounted upon the hub of the wheel 28, is a collar 31, one end of which is conical, as clearly shown in Fig. 18, which operates 120 when said collar is thrust inwardly toward the wheel 28, to engage behind a pin 32, on the tail of the pawl 29, thus thrusting the tail of the pawl outwardly against the stress of its spring 30, and withdrawing the 125 toothed end of said pawl radially inwardly out of engagement with the notch in the circular flange of the wheel 24, so that the drive from the wheel 24, to the wheel 28, is disconnected.

The mechanisms which serve to operate the slidable collar 31, will be hereinafter referred to in the description of the automatic means which operates to bring the machine 5 to rest after a predetermined number of coins have been counted.

Another shaft 33, is journaled above the shaft 23, and is driven thereby at a reduced speed by intermeshing gears 34 and 35, respectively, secured on said respective shafts 33 and 23. A sprocket wheel 36, is secured upon said shaft 33, and trained thereabout is a sprocket chain 37, which is also trained about the sprocket wheel 18, on the shaft 17, so that said shaft 17, is driven by the shaft 33, when the clutch 19, on said shaft 17, is engaged. Bracket plates 38 and 39, respectively, are supported on the forward extensions of the bracket members 15 and 20 16, as clearly shown in Figs. 1 and 14, and supported thereon is a circular frame plate 40, having an integral flat extension 41, at one side thereof, as clearly shown in Fig. 8. Secured in upright position upon the frame 25 plate 40, is a cylindrical curved wall 42, shown in Figs. 3 and 4, having a straight side portion 43, at one side, as clearly shown in Fig. 3.

Journaled flat upon the plate 40, is a circular centrifugally operating coin wheel 44, having a downwardly extending hub 45, which extends through a bearing 45^a, formed integral on the bottom of the plate 40, and has secured therethrough an upwardly extending shaft 46^a. Secured upon the lower end of the shaft 46^a, is a bevel gear 46, which meshes with a bevel gear 47, secured upon the shaft 33, as shown in Fig. 14. Secured upon the upper end of the shaft 46^a is a small bevel pinion 48, the hub of which is journaled in a bearing bracket 49, which is suspended upon a horizontal shaft 50, journaled in opposite sides of the wall member 42-43. Secured upon said shaft 50, between the arms of the bracket 49, is a small bevel pinion 51, meshing with the bevel pinion 48, whereby said shaft 50, is driven by the shaft 46^a. Secured upon one end of the shaft 50, is a friction wheel shown in detail in Fig. 7, comprising a peripherally grooved disk 52, with a rubber tire 53, engaged therearound and held in position by a cover plate 54, which is secured upon said disk. Said friction wheel, as clearly shown in Figs. 3 and 4, rotates in a vertical plane spaced slightly above the flat horizontal coin wheel 44.

Mounted within the wall member 42, is a vertically adjustable annulus 55, the lower surface of which is spaced slightly above the coin wheel 44, sufficiently to allow only coins of a certain thickness or denomination to pass thereunder due to the centrifugal effect on the coin of the rapidly rotating coin wheel 44.

As shown in the detail view in Fig. 9, said

annulus 55, is slotted in its upper surface at a plurality of points, and engaged in each slot is a head 56, on the lower end of a screw 57, provided with an actuating member 58, on its upper end, whereby the screw may be rotated, and said screw has threaded engagement through an inwardly projecting lug 59, secured upon the wall member 42. There are three of said adjusting screws to regulate the height of the annulus 55, above the coin wheel 44, as shown in Figs. 2 and 3.

Mounted in inclined position at the forward end of the machine between the side walls 2 and 3, is an inclined chute 60, which serves to receive the coins discharged thereon from the tray conveyer and direct the same onto the coin wheel 44, which, rotating at a high rate of speed, serves to throw the same to the outer periphery thereof, the coins of the proper thickness readily sliding beneath the annulus 55. The coins are then whirled around upon the coin wheel, and carried toward and beneath the rapidly driven friction wheel 52, which upon contacting the upper surface of a coin introduced therebeneath, assists in driving the same against the star wheel 61, shown in Fig. 8. An adjustable guide or stripper bar 62, is provided mounted between the surface of the coin wheel 44, and the wall member 43, as shown in Figs. 3, 4 and 8, to permit passage toward the star wheel 61, of the coins only in single order. For the purpose of adjustment of the guide bar 62, for coins of different denominations, the same is pivoted upon a pintle 63, which is secured in the under surface of the wall 43, and said wall member 43, is provided with a series of apertures 64, adapted to receive a pin 65, projected therethrough to engage one of a series of apertures 66, in the guide bar 62.

A detent member to prevent overtravel of the star wheel 61, is provided comprising a small lever 61^a, pivoted at one side on the frame plate extension 41, provided with a roller, for engagement with the periphery of the star wheel, and normally impelled into engagement therewith by a leaf spring.

As clearly shown in Fig. 4, a vertical shaft 61^b, extends upwardly from the frame plate extension 41, on which said star wheel 61, is secured, and on the upper end of said shaft 61^b, is a bevel pinion 61^c, meshing with a bevel pinion 67, which is secured upon the end of a horizontal shaft 68, journaled in bearing members 69, formed upon a frame plate 70, which is supported above the frame plate extension 41. Secured near the other end of said shaft 68, is a pinion 71, which meshes with the pinion 72, secured upon the shaft of a counter or register 73, which is mounted on the frame plate 70. A relatively large pivot stud 74, is secured in the frame plate 70, and pivoted thereon is a flat bar 75, extending normally substantially parallel

to said shaft 68. An upright stud 76, is secured on said bar 75, and journaled on the upper end thereof is a worm gear 77, which meshes with a worm 78, secured upon the shaft 68. A short brace bar 78^a, is connected between the respective pintles 74 and 76, as clearly shown in Fig. 5, disposed above the worm gear 77. Another stud 79, is secured to the bar 75, and journaled thereon is a mutilated idler pinion 80, which, as shown in Fig. 12, is provided with six teeth, alternate ones of which are only of half thickness. Also journaled upon the stud 76, and secured beneath the worm gear 77, to rotate therewith, is a double thickness gear disk element 81, which, as shown in Fig. 12, has its lower thickness provided with two teeth 82, and its upper thickness with a tooth recess therebetween denoted by the reference numeral 83, and said gear disk 81, by one complete rotation is adapted to move the mutilated gear 80, a distance of two teeth. Another stud 84, is secured to the other end of the flat bar 75, and journaled thereon is a cylindrical member 85, which is surrounded by a ring gear 86, in mesh with the idler pinion 80. Vertically slidable within the cylindrical member 85, is a sleeve element 87, having an actuating head 88, threaded on the upper end thereof, and coiled within said sleeve element 87, is a spiral compression spring 89, which is seated beneath the head of the stud pintle 84, and acts to resist upwardly sliding movement of said sleeve. As clearly shown in Fig. 10, a stationary stop 90, is secured upon the bar 75, and another stop member 91, is secured at the zero mark of the ring gear 86, which strikes the stop 90, when the ring gear 86, is rotated to zero position.

Disposed beneath the head 88, is a circular ring portion of a pointer 92, shown in Figs. 3 and 10, and this pointer 92, is adapted to strike against a flange 93, formed on the hub 45 of a cam 94, which is feathered upon the shaft 68, to slide said cam along, whereby as the same rotates it may strike against the upper end of a lever 95, which is mounted on a pivot beneath the frame plate 70, as shown in Fig. 10, and the lower end of which extends downwardly through a slot in the frame plate extension 41, and has a lever 96, connected thereto. Said pointer 92, is provided with a pin adapted to be engaged in 55 any one of a series of apertures in said member 85, and is held locked in certain relation with the member 85, and its ring gear 86, by the spring thrust head 88, but the position of the pointer with reference to said 60 ring gear may be changed by elevating the head 88, and the pointer 92. The position of the pointer 92, with reference to said ring gear 86, determines the number of coins to be counted before the machine is brought to 65 rest.

The lever 96, as shown in Fig. 8, is connected to one end of a crank 97, pivoted beneath the frame plate extension 41, and connected to the other end of said crank 97, is a long link 98, which is connected to one 70 end of a pivoted lever 99, the other end of which is forked and engages in the groove of the clutch throw-out member 31.

As clearly shown in Figs. 8 and 16, a downwardly directed coin chute 100, is secured beneath the frame plate 40, with the open mouth of the coin chute in line with the path of movement of the coins as they move from engagement with the star wheel 61, positively ejected, by the rapidly rotating friction wheel 53, so that said coins fall downwardly through said coin chute or tube 100, into a bag or packaging attachment which may be connected thereto. Receiving trays 101 and 102, are mounted at each side 80 of the machine as clearly shown in Fig. 2, to permit the defective coins observed on the coin conveyer to be swept thereto by the inspector before passage to the counting mechanism. 90

The operation is as follows:

The coins to be inspected and counted are dumped into the hopper 4, at one end of the machine, and are carried therefrom upon the pans or trays 13, of the conveyor upwardly and then for a certain distance, horizontally, into the field of observation of an inspector, and if faulty or defective coins are discovered, the same are removed by sliding the same outwardly at either end of 100 the pans 13, onto either of the trays 101 or 102.

As shown in Fig. 19, a lever 103, is pivoted upon the surface of the frame plate 70, and is provided with a rounded portion 105 adapted to contact against the pivoted bar 75, to hold the same thrust against a spring 104, which normally tends to throw said bar 75, outwardly so that the worm wheel 77, carried thereon, will be thrown out of 110 mesh with the worm 78. Two stops 105 and 106, respectively are provided on the frame plate 70, to limit the movement of the lever 103, which serves to hold the bar 75, in 115 position so that the worm wheel 77, is in driving engagement or out of driving engagement as the case may be, with the worm 78. The coins which pass inspection, travel on with the conveyer and are discharged down the chute 60, to the counting mechanism. 120

The counting mechanism is adapted to count the coins of different denominations by first adjusting certain parts of the mechanism, so that any coin of a greater thickness or diameter than that for which the machine is adjusted will not be counted. The mechanism for limiting the admission of the coins to be counted to those of a certain thickness is the vertically adjustable annu- 125 130

lus 55, which is disposed above the outer periphery of the centrifugal coin wheel or disk 44, as shown in Fig. 9, and the mechanisms which serve to limit admission of coins to 5 the register actuating means according to their diameter, is the guide lever 62. The annulus member 55, may be adjusted to different heights above the coin wheel 44, by turning the heads 58, thereby rotating the 10 elevating screws 57. The guide lever 62, may be adjusted to different positions by movement about its pivot 63, and thereafter locking the same by means of the pin 65, engaged through one of the apertures 64, 15 of the wall member 43, and also through one of the apertures 66, of said lever 62. The coins which are discharged down upon the coin wheel 44, from the conveyer, slide outwardly to the periphery thereof beneath the 20 annulus 55, due to the centrifugal effect of the rapidly rotating wheel 44, and are carried behind the lever 62, and into engagement with one of the notches of the star wheel 61, shown in Fig. 8. At this instant, 25 the coin also passes beneath the rapidly rotating friction wheel 53, which contacting the upper surface thereof, serves to aid in thrusting the same past the star wheel 61, thereby rotating said star wheel and further insuring ejection of the coin to the 30 discharge chute or tube 100. Each movement of the star wheel 61, by a coin is transmitted through suitable gearing to the register 73, and the movement is also imparted to the 35 mechanisms which limit the operation of the machine to a count of a predetermined number of coins.

The machine may be set to count any number of coins desired, at the end of which the 40 machine automatically stops operation. For this purpose, the pointer 92, is set to a certain position with reference to the ring gear 86, which is first reversely rotated to initial position, that is, with the stop 91, thereon, 45 against the stop 90, such reverse rotation being permitted by releasing the lever 103, to swing the bar 75, outwardly so that the worm gear 77, is not in mesh with its worm 78.

50 After the gear 77, has been swung into engagement with its worm 78, and the machine started in operation, the coins are carried upwardly by the conveyer and discharged upon the coin wheel 44, and carried thereby 55 past the star wheel 61, actuating the register mechanism and also driving the worm gear 77, which, by each rotation, serves to drive the idler pinion 80, imparting movement thereby to the ring gear 86, to shift the 60 pointer 92. As the number of coins counted approaches the limiting number thereof to be counted, the pointer 92, strikes against the flange 93, to shift the cam 94, upon the shaft 68, so that the cam teeth on said cam 65 94, in its next revolution, will strike the up-

per end of the lever 95, as shown in Fig. 10, thereby actuating the lever 96, and through it, the link 98, which operates the lever 99, to thrust the clutch throwout collar 31, inwardly. The inward movement of the collar 31, serves to strike against the pin 32, thereby retracting the pawl 29, out of engagement with the notch in the pulley 24, and disconnecting the drive from the machine. 75

I am aware that various details of construction may be varied through a wide range without departing from the principles of this invention, and I therefore do not purpose limiting the patent granted otherwise than necessitated by the prior art. 80

I claim as my invention:

1. In a machine of the class described a hopper, an annulus vertically adjustable in the hopper to provide a space beneath the same and bottom of hopper, counting mechanism to receive the coin comprising a centrifugal wheel rotating below the annulus on which the coins are discharged, a star wheel to which the coins are carried by said centrifugal wheel, a shaft extending across the top of the hopper, a friction wheel on the end thereof co-acting with a coin to thrust the same past the star wheel to actuate the star wheel, registering mechanism actuated by said star wheel, and a stop mechanism operated in conjunction with the registering mechanism to disconnect the drive from the machine after a predetermined number of coins have been counted. 100

2. In an inspection and coin counting machine of the class described, a hopper, lugs secured to the side wall of the hopper, an annulus in the hopper, screws threaded through the lugs rotatably engaged to the annulus adapted to elevate or depress the annulus, a counting mechanism comprising a centrifugal coin wheel rotatable in the bottom of the hopper operating to discharge the coin through the periphery thereof beneath the annulus, means limiting travel of coins on said coin wheel, to coins of certain diameter toward counting position, a star wheel adapted to receive the coins projected thereagainst, means driving a coin as a mechanical element past said star wheel to actuate the star wheel, registering mechanism driven by the star wheel, and means adjustable and driven by said star wheel to cut off the drive to the machine after a predetermined number of coins have been counted. 110

3. In a machine of the class described, a counting device embracing a rapidly rotating horizontal coin wheel by which the coins are centrifugally discharged through the periphery thereof, means limiting movement of coins of a certain diameter through the periphery of said wheel, a friction wheel mounted at one side of said coin wheel above the same, and driven coincidentally there- 125

with beneath which coins are constrained to pass, a counting mechanism actuated by the coins as the same pass said friction wheel, a stop mechanism adapted to disconnect the 5 drive from the machine, a pivoted bar, a mechanism carried by said bar operated from the counting mechanism adapted to be set to operate the stop mechanism, and a spring for shifting the same out of 10 operative position.

4. In a machine of the class described a hopper, a centrifugally operated horizontal coin wheel, means vertically adjustable in the hopper for limiting movement of coins 15 thereon to the outer periphery thereof to coins of a certain thickness, a star wheel with which said coins are carried into engagement by said coin wheel, friction means disposed above the coin wheel to assist 20 carrying the coins past said star wheel to actuate the same, registering mechanism driven by the star wheel to affect a count of the coins carried past said star wheel, a stop mechanism, a pivotally mounted mechanism 25 driven from the star wheel adapted to actuate the stop mechanism, a spring for forcing the pivotally mounted mechanism into inoperative position and a cam lever for holding the pivotally mounted mechanism 30 in operative position.

5. In a machine of the class described a hopper, a centrifugal coin carrying wheel therein, an annulus adjustable in said hopper, means rotatably connected to said annulus for adjusting the same to and from said coin carrying wheel, a shaft journaled in said hopper, a friction wheel thereon adapted to engage coins from said carrying wheel, a star wheel adapted to be actuated 40 by said coins, a shaft rotated by said star wheel, a register, a shaft rotated by the star wheel shaft adapted to actuate said register, a pivotally mounted bar, a gear on said bar driven from one of said shafts, a stop mechanism pivoted on said bar adapted to be operated by said gear and mechanism on the second named shaft co-acting therewith to disconnect the drive for the machine.

6. In a device of the class described, a 50 drive shaft, a clutch element thereon, a register, a centrifugally acting coin carrying wheel, means adapted to push coins off of the carrying wheel, mechanism operated by said coins for actuating said register, a mechanism adapted to disengage said clutch, a cam for actuating said mechanism, and a pivotally mounted stop mechanism adapted 55 to actuate said cam.

7. In a machine of the class described a 60 driven shaft, a hopper, a rotatable coin carrying wheel therein, a friction wheel adapted to pick coins from said coin wheel and advance the same, a star wheel engaged by said coins, a register mechanism connected to be operated from said star wheel,

a pivotally mounted clutch mechanism, a cam for actuating the same, a stop mechanism for adjusting the cam to engage said pivotally mounted mechanism and means for returning the stop mechanism to normal.

8. In a machine of the class described a centrifugally acting coin wheel, a friction wheel adapted to engage the coins and advance the same, a register, a shaft connected to actuate the register, a star wheel connected to actuate said shaft and adapted to be actuated by the coins, a gear on said shaft, a pivotally mounted bar, a gear journaled thereto adapted to register with the 80 aforesaid gear, a timing mechanism on the pivoted bar actuated by said gears, a cam on said shaft adapted to be shifted by the timing mechanism and a clutch shifting mechanism adapted to be shifted by said 85 cam.

9. In a device, a hopper, a centrifugal coin wheel rotatable on the bottom of the hopper, a member vertically adjustable in the hopper adapted to be set for coins of 90 different thickness to pass thereunder on the coin wheel, a lever adjustable beneath said member to constrain the coins passing in single file, a friction wheel under which the coins pass, a star wheel, a shaft operated 95 therefrom, a register actuated from said shaft, a cam slidable on the shaft, a gear on the shaft, a pivotally mounted mechanism actuated from the gear adapted to be set to shift the cam at a predetermined 100 count, a clutch shifting mechanism operated by the cam, means for automatically shifting the pivotally mounted mechanism to disengage the same from the gear to permit the cam shifting mechanism being set to 105 zero and means for shifting the pivotally mounted mechanism to engage the gear.

10. In a machine of the class described a hopper, a coin wheel therein, a shaft extending centrally into the hopper connected to 110 rotate the wheel, a shaft extending across the top of the hopper, intermeshing gears on said shafts, a friction wheel on the end of the second named shaft, an annulus in the hopper, members pivoted thereto 115 adapted to vary the vertical adjustment of the annulus, and a registering mechanism actuated by coins as they pass beneath the friction wheel.

11. In a machine of the class described a 120 hopper, a coin wheel therein, a shaft extending centrally into the hopper connected to rotate the wheel, a shaft extending across the top of the hopper, intermeshing gears on said shafts, a friction wheel on the end 125 of the second named shaft, an annulus in the hopper, members pivoted thereto adapted to vary the vertical adjustment of the annulus, a registering mechanism actuated by coins as they pass beneath the friction 130

wheel, a clutch shifting mechanism, means for actuating the same, a pivoted bar, a plurality of studs secured thereto, and a timing mechanism mounted on said studs adapted to shift the cam at the end of a predetermined count by the register.

In testimony whereof I have hereunto

subscribed my name in the presence of two subscribing witness.

JAY M. JOHNSON.
